212,876

MOBILE CARGO CONTAINER HANDLER

Charles D. Ramsden, Alameda, Charles H. Zweifel and
Anthony J. De Stasi, Oakland, and Arnold Wolf,
Berkeley, Calif., assignors to Pacific Coast Engineering
Company, a corporation of California

Filed June 12, 1967, Ser. No. 7,442

Term of patent 14 years

(Cl. D14—3)

THE
TIDE.

FIG. 3.

FIG. 4

FIG. 7.

FIGURE 1 is a front elevational view of a mobile cargo container handler showing our new design;

FIGURE 2 is a rear elevational view thereof;

FIGURE 3 is a left side elevational view thereof;

FIGURE 4 is a right side elevational view thereof;

FIGURE 5 is a top plan view thereof;

FIGURE 6 is a bottom plan view thereof; and

FIGURE 7 is a perspective view thereof.

The dominant features of our design reside in the portions shown in full lines.

We claim:

The ornamental design for a mobile cargo container handler, as shown and described.
